UNITED STATES PATENT OFFICE.

CHARLES PIEZ, OF PHILADELPHIA, PENNSYLVANIA, ASSIGNOR TO THE
LINK-BELT ENGINEERING COMPANY, OF SAME PLACE.

VALVE FOR CONVEYER-CHUTES.

SPECIFICATION forming part of Letters Patent No. 591,292, dated October 5, 1897.

Application filed November 7, 1896. Serial No. 611,420. (No model.)

To all whom it may concern:

Be it known that I, CHARLES PIEZ, a citizen of the United States, residing in Philadelphia, Pennsylvania, have invented certain Improvements in Valves for Conveyer-Chutes, of which the following is a specification.

The object of my invention is to provide a chute for feeding material into a continuously-moving bucket conveyer with a valve which is so geared to the driving mechanism of the conveyer that it will regulate the flow of material into the buckets and prevent the overcharging of the same.

My invention is especially adapted for use when material in large lumps, such as large-sized coal, is to be loaded into the buckets. I find in practice that small material will flow from the chute into the buckets in a steady stream, while large material requires a very large opening for a free discharge, and this discharge is uneven, causing some of the buckets to be overcharged, while others are undercharged; but by my invention I am enabled to so regulate the discharge of material that all the buckets will be loaded with the same amount of material.

In the accompanying drawings, Figure 1 is a longitudinal sectional view of sufficient of a conveying apparatus to illustrate my invention, the conveyer being in section; and Fig. 2 is a perspective view of the valve which I provide at the end of the chute.

A is sufficient of an endless-chain bucket conveyer to illustrate my invention, the buckets *a* being secured to the chain-links *a'*, and the links are provided with wheels *a''*, adapted to the tracks *B*. Each conveyer-bucket has a hood *a'*, so that the bucket can be reversed on the upper run without discharging the material.

A charging-opening *c* is left in the front of the bucket, so as to receive the material discharged from the chute. I do not claim this form of conveyer, as my invention can be used in connection with other forms of conveyers as well.

D *D* are chutes which are arranged at any incline, and each communicates with a hopper or bin *D'*.

In feeding small material, such as small-sized coal and grain, to the conveyer the valve

mechanism may be dispensed with and the throat of the chute may be reduced to any-sized opening required, as the small material will have a regular flow, but large material, such as broken coal, cannot be fed in an even stream from the hopper. The opening connecting the hopper with the chute must be considerably larger than the ordinary opening to prevent the bridging of the material, but this opening is of necessity too large to allow for the even flow of material. Sometimes the material will flow so as to overload the buckets, and at other times it will be clogged, so that very little material will escape into the buckets, but by providing a valve at the outer end of the chute which will have a regular motion as each bucket comes under it I am enabled to bank up the material in the chute and feed at intervals a given quantity sufficient to properly load each bucket, as it will be understood that if the buckets are overcharged a waste of material naturally results.

E is a valve at the end of a chute, and in the present instance this valve has two arms *E'*, pivoted at *e* to the sides of the chute, and these arms are extended beyond the pivots and are preferably slotted, and adapted to the slot in each arm is a pin *f*, projecting from a bar *F*, hung by links *f'* from any suitable support.

Connected to the bar *F* is a rod *G*, which in turn is connected to the crank *h* of the shaft *H*, adapted to suitable bearings. This shaft *H* is driven from the shaft *A'* of the conveyer mechanism, in the present instance through an inclined shaft *H'* and bevel-gears, as shown in Fig. 1, so that the valve will open the chute when the mouths of the buckets are in proper position.

The valve moves from the bottom up, so as to cut up through the material, preventing the flow when the valve is in the position shown in Fig. 1; but when the valve is lowered the material will freely flow from the chute. By this construction I avoid any clogging whatever as the valve moves up through the material.

In the drawings I have shown two chutes, each provided with a valve. The valve of one chute is coupled to the reciprocating bar *F*, while the other valve is disconnected. By

this arrangement I can operate any one valve of a series, so that the conveyer can be loaded with different grades of material.

It will be understood that while my invention is adapted especially to lumpy material, such as broken coal, it can be used on finer material with the same result, although a valve in this case is not necessary to properly fill the buckets.

10 I claim as my invention—

1. The combination of a conveyer, a feed-chute, a valve at the end of the feed-chute adapted to travel in a segment of a circle, arms on the said valve pivoted to the chute, 15 said arms having extensions, a bar adapted to engage with the said extensions, links suspending the said bar, a driving-shaft, a crank thereon and a rod connecting the said crank to the bar, substantially as described.

20 2. The combination of a series of feed-

chutes, valves therefor, an operated bar and means for connecting any one of said valves to the bar, substantially as described.

3. The combination of an endless-chain bucket conveyer, driving mechanism therefor, a feed-chute above the open mouth of the conveyer-buckets, a valve for the feed-chute acting intermittently to cut off the flow of material from the chute during the travel of the conveyer so as to uniformly load 25 the buckets, and means connecting the valve with the driving mechanism of the conveyer, substantially as described.

In testimony whereof I have signed my name to this specification in the presence of 30 two subscribing witnesses.

CHARLES PIEZ.
